UNITED STATES PATENT OFFICE.

JOSIAH C. GOODING, OF ST. LOUIS, MISSOURI.

DESIGN FOR A SEAT.

SPECIFICATION forming part of Design No. 25,734, dated June 30, 1896.

Application filed May 28, 1896. Serial No. 593,517. Term of patent 14 years.

To all whom it may concern:

Be it known that I, JOSIAH C. GOODING, a citizen of the United States, residing at St. Louis, in the State of Missouri, have invented 5 and produced a new and original Design for a Seat, of which the following is a specification, reference being had to the accompanying drawings, showing a part thereof.

Figure 1 represents a side view of a seat 10 embodying my design, and Fig. 2 is a perspective view.

The leading feature of my design consists in a vertically-disposed side panel having a straight lower edge and an otherwise approximately oblong and curvilinear contour, and having the surface of the obverse side thereof embossed in representation of a twig or spray 15 of leaves pointing or trending upward, as well as with a beading or molding surrounding or 20 inclosing the spray and following the general direction of and lying within the edge or border-line of the panel.

In the drawings the seat is represented as a whole by the letter A, and B is the seat 25 proper. The back of the seat is designated at C, and the side panel at D. As viewed in side elevation at Fig. 1, the side panel is vertically disposed and the rear edge 2 thereof is substantially straight, the forward edge 3 30 being slightly curved and inclined rearward as it rises, and the two edges being united or joined at the lower end of the panel by a straight horizontal edge 4. The said edges 2 and 3 intersect or join each other at the upper 35 tapered end of the panel in a curved line or edge 5, thus approximating an oblong and curvilinear contour. The outer or obverse side of the panel is embossed with a continuous beading or molding 6, lying a suitable 40 distance within and following the general direction of the outer edge or border-line of said panel; and also embossed thereon is a twig or spray of leaves 7, pointing or trending up-

wardly, as shown. The said panel is of sheet metal and forms an outer facing for the framework of the seat, the said frame work being designated at E, and comprising a strip of angle metal bent or shaped into the same general contour as the panel, the edges of the two being flush where joined, and the frame being extended a suitable distance at each end to constitute the supporting-legs 9 45 10, which are reversely bent or curved in opposite directions at 10^a, to constitute, respectively, the feet 11 and 12. 50

The seat proper, B, in the side view is indicated by the double horizontal lines 13 14, projecting from the forward edge of the panel at right angles, and 15 designates a piece of frame intersecting the seat and frame E in a 55 diagonal direction. As viewed in perspective, the back C is shown as between two of the panels and frames above described, and the same is set in, so as to bring its surfaces within the edges of the panels and frames, as shown 60 at 16. The lower edge of the back is straight at 17, and the upper part thereof is oval or rounded at 18, giving it the appearance of being doubled over, so as to extend down in the same manner on the 65 opposite side. There is a space 20 between the lower straight edge 17 of the panel and the corresponding inner straight edge 21 of the seat proper, the remaining portion of the latter (the seat) being in this figure bounded 70 by the lines 22, 23, and 24. 75

What I claim, and desire to secure by Letters Patent of the United States, is—

The design for a seat substantially as herein 80 shown and described.

In testimony whereof I affix my signature in presence of two witnesses.

JOSIAH C. GOODING.
